UNITED STATES PATENT OFFICE.

FRANK E. FISHER, OF DETROIT, MICHIGAN.

STARTER FOR INTERNAL-COMBUSTION ENGINES.

1,295,144.

Specification of Letters Patent. Patented Feb. 25, 1919.

Application filed February 18, 1918. Serial No. 217,773.

To all whom it may concern:

Be it known that I, FRANK E. FISHER, citizen of the United States, residing at Detroit, county of Wayne, State of Michigan, have invented a certain new and useful Improvement in Starters for Internal-Combustion Engines, and declare the following to be a full, clear, and exact description of the same, such as will enable others skilled in the art to which it pertains to make and use the same, reference being had to the accompanying drawings, which form a part of this specification.

My invention relates to a starter for internal combustion engines and is especially designed for use upon an automobile of the "Ford" type.

It is well known that the available space on a Ford automobile for the installation of a device of this character is very limited and when installed it is desirable that it should be done without interfering with any of the working parts of the motor or vehicle;—at a minimum cost;—and be readily accessible for inspection or repairs.

It is therefore one of the objects of this invention to provide means for supporting an "electric starter and generator unit" by substituting for the usual front cover plate of the cylinder of the motor, a cover plate adapted to meet not only the requirements of the motor, but upon which the "electric starting and generator unit" is adapted to be bolted that it may be supported thereby.

A further object of the invention is to provide for the ready inspection, or removal of the electric starter and generator unit for repairs, without disturbing any of the parts relating to the motor.

A still further object is to provide registering means, whereby the replacing and securing of the electric starting and generator unit upon the supporting cover plate of the motor may be rapidly and accurately accomplished.

In chain driven devices of this character, it has been found in practice, that on account of carelessness in the adjustment of the spark control that the chain is sometimes broken through "back-firing" of the motor.

One of the features therefore of the present invention is the employment of a train of gears connecting the generator shaft of the starting unit with the crank-shaft of

the engine, in lieu of the chain driving connection commonly employed, in order that the objection referred to may be overcome.

A further object of the invention is the employment of means adapted to serve as a "shock absorber" between the crank-shaft of the engine and the starting unit, in order to relieve the strain due to "back-firing" of the engine.

With the foregoing and other objects in view which will appear as the description proceeds the invention resides in the combination and arrangement of parts and in the details of construction hereinafter described and claimed, it being understood that changes may be made in the precise embodiment of the invention herein disclosed without departing from the spirit of the same.

In the drawings accompanying this specification:—

Fig. 1 is an end elevation of a "Ford" motor secured to its supporting frame with an electric starting and generator unit installed thereon, the same being mounted on a cover plate especially designed for the requirements of the motor and for supporting the starting unit.

Fig. 2 is a side view of the starting unit and a fragmentary portion of the motor.

Fig. 3 is an elevation of the cover plate of the cylinder and the end plate of the starting unit bolted thereto.

Fig. 4 is an enlarged detail cross-sectional view on line 4—4 of Fig. 3, showing a tongue and groove connection between the respective cover plates of the cylinder and starting unit, to provide for rapid and accurate assembling of the parts.

Referring now to the letters of reference placed upon the drawings:

A, denotes the supporting frame of an automobile. B, indicates an internal combustion engine bolted thereto, that shown being of the "Ford" type of motor. C, designates a cover plate for the engine cylinder which in the present invention is substituted for that usually employed on the Ford motor, the construction being such as to adapt it to fully meet the requirements of the engine and in addition to receive and support an electric starting and generator unit D, secured thereto.

E, indicates a gear keyed to the crank-shaft of the engine in mesh with a gear F, supported by a stub shaft journaled in the

cover plate C. G, denotes a shock absorbing gear,—similar in character to that shown in my application for patent Serial No. 211,135 for engine starter, filed January 10, 1918,—5 mounted upon the generator shaft H of the starting unit and in mesh with the gear F. The shock absorbing gear G is provided with suitable cushioning means which is interposed between the gear and the generator shaft for absorbing and dissipating the shocks to prevent the same from being transmitted to the generator shaft. As the starting and generator unit proper forms no part of this invention and is otherwise shown in 10 the application referred to it will be unnecessary to go into a detailed description of the same. I, indicates an end cover plate bolted to the case of the starting unit D, having a projecting flange V, encircling the 15 gear G; and C', is a like flange projecting from the plate C, encircling the gear F. To the flanged portion of the plate C, and I, are bolted cover plates, (not shown) secured by bolts engaging the lugs c, and i, of the 20 respective plates.

Extending laterally from the flanges of the plates C, and I, are abutting portions Q², and I², having a tongue and groove connection I³, that the parts may be readily assembled and properly centered. C² are transverse bolts to secure the starting and generator unit to the plate C.

Having indicated the several parts by reference letters, it will be readily seen that the 35 starting and generator unit may be readily removed for inspection or repairs upon the withdrawal of the bolts C², securing it to the supporting plate C;—the latter also forming the cover plate of the engine cylinder.

40 It will also be apparent that by providing a train of gears between the generator shaft of the starting unit and the crank-shaft of the engine to "turn over" the latter, in place of the usual driving chain connection, that 45 the danger of damage to the driving connection through "back-firing" of the engine will be practically or entirely overcome.

And as a further safeguard against injury to the driving connection it will be evident 50 that the shock absorbing gear, employed in the train of gears connecting the starting unit with the crank-shaft of the engine, will also serve to relieve any undue strain caused by the back-firing of the internal combustion engine.

Having thus described my invention what I claim is:

1. In a device of the character described, a cover plate for the cylinder of an internal 60 combustion engine having opposite projecting portions located at one side of the upper portion of the said cover plate, an electric starting and generator unit, a plate bolted to said unit having projecting portions 65 adapted to abut against the projecting por-

tions of the cover plate of the engine cylinders, said plates being arranged in substantially the same transverse plane, and bolts for securing the projecting portions of said respective members together, whereby the 70 starting unit is supported.

2. In a device of the character described, a plate adapted to serve as the front cover of a Ford motor cylinder and having opposite projecting portions located at one side of the 75 upper portion of the cover plate, an electric starting and generator unit, an end plate bolted to the end of said unit having projecting portions adapted to abut against the projecting portions of the cylinder cover, 80 said plates being arranged in substantially the same transverse plane, and bolts extending through said projecting portions to secure said starting and generator unit to the cover plate of the cylinder.

3. In a device of the character described, an engine, a crank-shaft, a front cover plate for the cylinder of the engine having opposite projecting portions located at one side of the 90 upper portion of the cover plate and perforated for the passage of belts, an electric 95 starter and generator unit, an end plate for said unit having projecting portions adapted to abut against the projecting portions of the cylinder cover plate, said abutting projecting portions formed with a co-acting tongue and groove to facilitate registration

and proper assembling of the parts and interlocking the said projecting portions, bolts for securing said projecting portions together, a train of gears adapted to provide a driving relation between the crank-shaft of the engine and the generator shaft of the starting unit, and flanges projecting respectively from the front cover plate of the cylinder and the cover plate of the starter unit to inclose and protect the gears.

4. In a device of the character described, an engine, a crank-shaft, a front cover plate for the cylinder of the engine having projecting portions to support a starter unit, an electric starter and generator unit, an end plate for said unit adapted to abut against the projecting portions of the cylinder cover plate in substantially the transverse plane 115 of the cover plate, bolts for securing the abutting projecting portions together to support the unit, a train of upper, lower and intermediate gears adapted to provide a driving connection between the engine 120 crank-shaft and the generator shaft of the starter unit, and a shock absorbing means in line with said train of gears, whereby the strain upon the driving mechanism due to back-firing of the engine may be relieved.

5. In a device of the character described, an engine, a crank shaft, a front cover plate for the cylinder of the engine having opposite projecting portions and provided with opposite flanges extending downwardly 130

therefrom, an electric starter and generator unit, and end plate for said unit provided with opposite portions abutting against the projecting portions of the cover plate and 5 interlocking therewith and secured thereto, said end plate being provided with upwardly extending flanges forming continuations of the flanges of the cover plate and a train of gears connecting the starter unit with the crank shaft and arranged within the flanges. 10 In testimony whereof, I sign this specification in the presence of two witnesses,

FRANK E. FISHER.
